UNITED STATES PATENT OFFICE.

CHARLES S. WALDO, JR., OF BROOKLINE, MASSACHUSETTS.

COVER FOR ASH-CANS.

1,161,089.

Specification of Letters Patent. Patented Nov. 23, 1915.

Application filed January 9, 1915. Serial No. 1,268.

To all whom it may concern:

Be it known that I, CHARLES S. WALDO, Jr., citizen of the United States, and resident of Brookline, in the county of Norfolk and State of Massachusetts, have invented 5 new and useful Improvements in Covers for Ash-Cans, of which the following is a specification.

This invention relates to covers for ash cans and similar receptacles, and its object 10 is to provide a novel and improved cover, suitable for use on any usual form of ash can, to keep the can tightly closed except when materials are being put in, and more 15 particularly to open when the materials are being put in and automatically to close again the moment the materials have passed through and the shovel or other implement being used has been withdrawn, thus effec- 20 tually preventing the escape of dust.

It is one of the important features of the invention that the lid is hinged to and operates within a casing supported wholly above the top of the can, so that the lid does 25 not swing down into the can when opened, thus leaving the entire space in the can free to receive the materials to the very top.

These and other features will be herein- 30 after more fully described and particularly pointed out in the claims.

In the accompanying drawings which illustrate one embodiment of the invention,—Figure 1 is a vertical section showing a cover containing the invention, supported 35 on the top of a can, with the lid in open position; Fig. 2 is a plan view of said cover; and Fig. 3 is an enlarged detail view in vertical section showing the dust proof cushion and the cover in closed position.

Referring to the drawings, A represents 40 an ash can, or similar receptacle, of ordinary form.

The cover comprises a base or platform B, circular in form and preferably provided 45 with a downwardly extending marginal flange b. The platform B rests on the top of the can after the manner of an ordinary cover, and is provided with a rectangular opening b'. Mounted on the platform B is 50 a rectangular casing C, three of the side walls of which rise from the edges of the opening b', so that a clear passage through the cover is provided, unobstructed by projecting ledges which might catch and accumulate ashes or other material, while the 55 fourth side wall of the casing rises from a

position removed from said opening b', thus leaving a shelf b² extending part way across the bottom of the casing. An opening c is provided in the top of the casing C, surrounded by a rim or flange which constitutes a seat for the lid when closed. 60

D is a downwardly swinging lid, hinged in the upper part of the casing C by means of pintles d, which extend through holes in 65 the side walls of the casing. Springs E of any approved type yieldingly hold the lid closed over the opening c. A cushion d' of felt or other suitable yielding material is secured about the margin of the lid D, and 70 forms a dust proof seal between the lid and the margin of the opening c.

The casing C is of such height above the base or platform B that the lid D will not swing downward into the ash space within 75 the can A, but substantially the whole range of movement of the lid will be within the casing C. Thus the can may be filled to its top without interfering with the operation of the lid. 80

The part of the platform which extends into the casing and forms the shelf b² serves as a stop to limit the downward movement of the lid and to hold it in an inclined position, as shown, so that it serves as an inclined chute for the ashes being inserted. 85 In that position the lid covers the shelf b² and prevents any of the ashes from lodging thereon.

The operation is as follows: It will be 90 understood that the lid is normally held closed by the springs. When ashes or the like are to be deposited in the can A, they are inserted through the opening c by means of a shovel or other suitable implement. The 95 user presses the lid downward with the shovel and permits the ashes to slide off, or the ashes may be deposited directly on the lid which will swing downward under their weight. In either case the ashes will pass 100 through the casing C and the opening b' in the platform, which is surrounded and enclosed by the casing, and the lid D will immediately swing upward again into closed position, preventing the escape of dust as 105 the ashes fall into the can.

The whole structure is preferably made of sheet metal, although that is not essential; and it may be made in sizes to conform to the standard sizes of ash cans, although the laterally extending platform B admits 110 of using the cover on cans of any circum-

ference between that of the flange b , and a circle circumscribing the opening b' . A strip of felt b^3 secured to the under margin of the platform B, constitutes a dust proof cushion between the platform and the top of the can A to prevent the escape of dust therebetween when the cover is in place.

I claim:

1. A cover for an ash can comprising a casing having an opening in its top, a base at the bottom of said casing adapted to rest on the top of the can and to support the casing above the top of the can, said base having an opening therethrough surrounded and inclosed by the casing, a downwardly swinging lid hinged to the casing having substantially its whole range of movement therein and adapted to close the opening in the top of the casing, and means yieldingly to hold said lid closed.
2. A cover for an ash can comprising a casing having an opening in its top, a base at the bottom of said casing adapted to rest on the top of the can and to support the casing above the top of the can, said base having an opening therethrough surrounded and inclosed by the casing, a downwardly swinging lid hinged to the casing having substantially its whole range of movement therein and adapted to close the opening in the top of the casing, a cushion of yielding material between the lid and the margin of the opening in the top of the casing, and means yieldingly to hold said lid closed.
3. A cover for an ash can comprising a casing having an opening in its top, a circular platform on which said casing is mounted, extending laterally beyond the walls of the casing and adapted to rest on the top of the can and to support the casing above the top of the can, said platform having an opening therethrough surrounded and inclosed by the casing, a downwardly swinging lid hinged to the casing having

substantially its whole range of movement 45 therein and adapted to close the opening in the top of the casing, and a spring yieldingly to hold said lid closed.

4. A cover for an ash can comprising a casing having an opening in its top, a circular platform on which said casing is mounted, extending laterally beyond the walls of the casing and adapted to rest on the top of the can and to support the casing above the top of the can, said platform having an opening therethrough surrounded and inclosed by the casing, a downwardly swinging lid hinged to the casing adapted to close the opening in the top of the casing, said platform also extending part way 60 across the bottom of the casing at the side at which the lid is hinged adapted to engage and stop the downwardly swinging lid in an inclined position, and a spring yieldingly to hold said lid closed.

5. A cover for an ash can comprising a circular platform having a rectangular opening therethrough, a rectangular casing mounted upon said platform three of the side walls of which rise from the edges 70 of said opening in the platform while the fourth side wall rises from a position on the platform removed from said opening, whereby a shelf is provided extending part way across the bottom of the casing, said 75 casing having an opening in its top, a downwardly swinging lid hinged to the upper part of the casing above said shelf and adapted to swing down into engagement with said shelf, and a spring yieldingly to 80 hold said lid closed.

Signed by me at Boston, Massachusetts
this 5th day of January 1915.

CHARLES S. WALDO, JR.
